DOUBLE WALLED FOUNTAIN

Jack R. Berry, Springfield, Ohio, assignor to The Buckeye Incubator Company, Springfield, Ohio, a corporation of Delaware

Application April 17, 1950, Serial No. 156,278

3 Claims. (Cl. 119—77)

1

This invention relates to fountains and more particularly to fountains for the watering of chickens, animals, and the like.

Double walled fountains are desirable as providing better temperature control, tending to prevent excessive heating of the liquid in summer as well as freezing in the winter. The present invention relates to such a double walled fountain in which the inner container is open at its top and permanently secured to the bottom or pan with a valve being provided in the lower portion of the side wall of said inner container which is normally biased toward closed position. This permits easy filling of the inner container and the carrying thereof to the point of use without loss of liquid from the fountain. The outer container or cover when placed in telescoping relation over the inner container is arranged to engage a valve actuating member, thereby releasing the water and allowing it to flow into the pan. However the cover is entirely closed except for its open bottom and its lower edge extends below the rim of the flange of the pan; hence upon being locked in place on the inner container it forms a siphon which prevents loss of water but which maintains a predetermined desired level in the pan for drinking purposes.

It is inconvenient to have to fit the cover in place where that operation requires the threading of pins and slots, such as in the case with a bayonet type of lock, particularly inasmuch as this engagement must be effected in an area which is somewhat obstructed and difficult to observe. In accordance with the present invention, a fountain of this construction is provided which does not require and interfitting of pins and slots and in which the cover may be lowered into place in a simple way, with the assurance that it will find its proper position without the necessity for careful guiding or indexing. Thereafter it may be locked in place by a simple twisting motion which does not require the engaging of pins or slots. Furthermore the twist to produce the locking action can be made in either direction relative to the inner container, a plurality of spaced locking members being provided such that this easily and quickly detachable locking action can be readily obtained.

It is therefore the object of the invention to provide a double walled fountain having an inner container and an outer cover in which the inner container can be first filled with water through its open top, and the cover then positioned thereover and secured in place by a simple twisting motion.

2

It is also an object to provide such a fountain in which the cover is guided into proper position without the need of careful handling or indexing, and which can be locked in operative position merely upon a twist in either direction.

Other objects and advantages will be apparent from the following description, the accompanying drawings and the appended claims.

In the drawings:

Fig. 1 is a view in reduced perspective of a fountain constructed in accordance with the present invention, a portion of the wall of the cover being broken away to illustrate the valve in the inner container;

Fig. 2 is a top plan view with parts of the top wall of the cover being broken away;

Fig. 3 is a partial side view in section taken on a diameter through the rivets 39 of Fig. 2, showing the top cover in locked position;

Fig. 4 is a partial view taken at right angles to Fig. 3 in section showing the cover in locked position;

Fig. 5 is a perspective view of the locking members secured to the inside of the cover; and

Fig. 6 is an enlarged fragmentary view in perspective of the handle or grip secured to the inner container which cooperates with the locking members.

Referring to the drawings which discloses a preferred embodiment of the invention the fountain is shown as comprising an inner container having a generally cylindrical side wall 10 with a rolled bead 11 at its upper end defining an opening 12 by means of which such container may be readily filled with liquid. The bottom end of the inner container is fixed in place upon the bottom wall 15 of a pan having an upwardly extending flange 16 terminating in a rolled edge or rim 17. An aperture 20 is formed in the lower part of the side wall of container 10 which is closed by a valve 21 normally urged to sealing position by means of a strap spring 22 secured to the outer wall of the container by welding the end 23 thereof to the surface of the container.

A handle in the form of a flat strap 30 is secured to the inner container, the handle having two vertically extending portions 31 secured to opposite sides of the inner wall of container 10 by a suitable means such as welding, and having a grip part 32 conveniently curved to be picked up by the hand and preferably located at a level above the bead 11 of the inner container.

The outer container or cover is shown at 35 and comprises an open bottom defined by a bead 36,

the diameter of the cover being slightly greater than that of container 10 so that it can be received in telescoping relation thereover. It will be evident from Fig. 1 that when so received and in operative position, the bead 36 extends into the pan below the level of the rim 17, thus forming a siphon controlling the level of the liquid in the annular drinking portion of the fountain. Except for its open bottom, the cover member 35 is entirely closed and sealed, having a conically shaped top portion 37 with an outer carrying handle 38 secured thereto by means of rivets 39 or the like.

On its inside top surface cover member 35 carries a locking structure indicated generally at 40. As shown in Fig. 5 this member is conveniently formed of a single piece of flat sheet metal stamped to conform to the inner surface of the cover itself, and with attaching holes 41 to receive the rivets 39 by means of which it is held in fixed relation within the cover. At each end the member is formed with a depending portion 42 which carries outwardly extending hook-shaped members 43, the top surfaces of which are suitably curved as shown at 44 to conform generally with the curvature of the under side of handle grip 32.

The operation of the fountain is as follows. With the cover removed the inner container is first filled with water or other liquid as desired, the valve 21 remaining closed under the action of spring 22 and thus preventing discharge of the liquid into the pan and making it possible to readily carry the filled container from place to place. When in its desired location the cover member 35 is merely placed over the inner container and lowered into position thereon. Toward the end of the lowering movement the wall of the cover bears against the curved spring member 22 pressing the valve inwardly to open position and allowing the liquid to flow outwardly into the annular drinking space of the pan. It will be evident that since cover 35 is completely sealed above its lower edge, the water level will be allowed to raise in the pan only to that point determined by the position of the lower bead 36 of the cover, thus maintaining the level in the fountain at a desired height.

With the cover so lowered it is conveniently locked in place merely by twisting the same relative to the inner container sufficiently to cause one or the other diagonally opposite pair of hook-shaped members to engage beneath the handle grip 32. Such twist can never exceed a half revolution, and is usually somewhat less. Further the twist can be produced in either direction since either diagonally opposite pair of such hook-shaped members will produce the same interfitting and locking action.

When so locked the fountain is ready for operation, and as will be evident it can also be transported from place to place by means of handle 38, if so desired. When refilling is desired, the cover can be detached readily by simply reversing the twist and lifting the same away from the inner container.

The invention thus provides a simple, easily operated and highly satisfactory double walled fountain construction which can be filled and used simply under all conditions.

While the form of apparatus herein described constitutes a preferred embodiment of the invention, it is to be understood that the invention is not limited to this precise form of apparatus, and that changes may be made therein without

departing from the scope of the invention which is defined in the appended claims.

What is claimed is:

1. A double walled fountain comprising an inner upright container having an open top and a closed bottom, a pan shaped portion extending outwardly of and substantially in the same plane with the bottom of said container, said pan shaped portion having an upwardly extending rim, a normally closed valve in the lower part of said container below said rim and having a part extending outwardly of the wall of said container, a handle adjacent the top of said inner container, an outer inverted cover open only at its bottom receivable in enclosing relation over said inner container and movable to an assembled position against a portion thereof in which position the lower edge of said cover is located above the bottom of said pan and below said rim with a portion of said outer cover in position to engage said valve to effect the opening thereof, and locking means carried on said cover member having interlocking engagement with said handle on said inner container upon relative twisting of said cover with respect to said inner container to releasably lock said outer cover in said assembled position thereon.

2. A double walled fountain comprising an inner upright container having an open top and a closed bottom, a pan shaped portion extending outwardly of and substantially in the same plane with the bottom of said container, said pan shaped portion having an upwardly extending rim, a normally closed spring-pressed valve in the lower part of said container below said rim and having a part extending outwardly of the wall of said container, a handle adjacent the top of said inner container, an outer inverted cover open only at its bottom receivable in enclosing relation over said inner container and movable to an assembled position against the upper end thereof in which position the lower edge of said cover is located above the bottom of said pan and below said rim with the side of said outer cover in position to engage said valve to effect the opening thereof, and a plurality of spaced locking members carried on the inside of said cover member having interlocking engagement with said handle on said inner container upon relative twisting of said cover with respect to said inner container to releasably lock said outer cover in said assembled position thereon.

3. A double walled fountain comprising an inner upright container having an open top and a closed bottom, a pan shaped portion extending outwardly of and substantially in the same plane with the bottom of said container, said pan shaped portion having an upwardly extending rim, a normally closed valve in the lower part of said container below said rim having a part extending outwardly of the wall of said container, a handle extending across the open top of said inner container above the liquid level therein, an outer inverted cover open only at its bottom receivable in enclosed relation over said inner container and movable to an assembled position against a portion thereof in which the lower edge of said cover is located above the bottom of said pan and below said rim with a portion of said outer cover in position to engage said valve to effect the opening thereof, and a plurality of pairs of spaced locking members carried on the inside of said cover member and arranged for interlocking engagement between diagonally opposite ones of said locking members with said

handle on said inner container in response to relative twisting of said cover member in either direction with respect to said inner container to releasably lock said cover in said assembled position thereon.
